DESIGN FOR A DISPLAY STAND

Frank C. Harbeson, Georgetown, Ind.

Application May 25, 1939, Serial No. 85,202

Term of patent 7 years

To all whom it may concern:

Be it known that I, Frank C. Harbeson, a citizen of the United States, residing at Georgetown, in the county of Floyd and State of Indiana, have invented a new, original, and ornamental Design for a Display Stand, of which the following is a specification, reference being had to the accompanying drawing, forming a part thereof, and in which the figure is a perspective view of the display stand, showing my design.

The appearance of the rear side of the book shaped element is similar in appearance to the front side illustrated.

I claim:

The ornamental design for a display stand, as shown and described.

FRANK C. HARBESON.
